UNITED STATES PATENT OFFICE.

AUGUSTINE C. WEST, OF CAMBRIDGE, MASSACHUSETTS.

DESIGN FOR AN OIL OR GAS STOVE.

SPECIFICATION forming part of Design No. 22,016, dated November 22, 1892.

Application filed September 26, 1892. Serial No. 446,956. Term of patent 7 years.

To all whom it may concern:

Be it known that I, AUGUSTINE C. WEST, a citizen of the United States, and a resident of Cambridge, in the county of Middlesex, State 5 of Massachusetts, have invented and produced a new and original design for a Gas or Oil Stove, of which the following is a specification, reference being had to the accompanying fac-simile drawing, forming part thereof.

10 The drawing herewith presented illustrates in a perspective view an oil or gas stove embodying my design.

The essential features of my design consist in a flat slab raised on supports above the 15 floor, a series of vertical columns or posts which is surmounted by a cover or top, and a central body.

10 The particular features of my design consist, furthermore, in a flat quadrilateral slab or base 20 2, beneath which are short pedestals or legs 3, longitudinally fluted. These legs extend above the slab and terminate in inverted-acorn-shaped tips, also fluted lengthwise. Beneath the slab is placed a rectangular-shaped 25 portion 4.

In addition to the above features are a num-

ber of upright columns 5, grouped upon the slab, and these act as a support for a top or cover 6. This cover is of quadrilateral shape and overhangs said columns, which are adorned 30 with a ribbon or band coiled about them. A pendent flange or lip 7 extends about the outer portion of the top and is pierced with a series of upright apertures 8, arranged near the middle part of the ends and side portions. 35 The upper surface of the top is molded and is here pierced with a series of upright rectangular apertures. The flat part of the cover is ornamented with a design of leaves, while an urn-shaped figure caps the whole. The 40 central body 9 is cylindrical and the columns 5 are grouped about it.

What I claim is—

The design for a gas or oil stove, substantially as herein shown and described. 45

In testimony whereof I affix my signature in presence of two witnesses.

AUGUSTINE C. WEST.
